UNITED STATES PATENT OFFICE.

LOUIS B. LONDON, OF NEW YORK, N. Y.

DESIGN FOR AN INVERTED-GAS-BURNER CROWN.

45,427.

Specification for Design.

Patented Mar. 17, 1914.

Application filed January 17, 1914. Serial No. 812,856. Term of patent 7 years.

To all whom it may concern:

Be it known that I, LOUIS B. LONDON, a citizen of the United States, residing in the borough of Manhattan, city of New York, county and State of New York, have invented a new, original, and ornamental Design for Inverted-Gas-Burner Crowns, of which the following is a specification, reference being had to the accompanying drawings, forming part thereof.

The figure is a side elevation of a crown for an inverted gas burner, showing my new design.

I claim:

The ornamental design for an inverted gas burner crown, as shown.

In testimony whereof, I have hereunto set my hand in the presence of the two subscribing witnesses.

LOUIS B. LONDON.
